PACKAGED SEED DISPLAY STAND

Earle E. Humphries, Los Angeles, Calif.

Application July 6, 1948, Serial No. 147,391

Term of patent 3½ years

(Cl. D80—10)

To all whom it may concern:

Be it known that I, Earle E. Humphries, a citizen of the United States of America and a resident of Los Angeles, county of Los Angeles, State of California, have invented a new, original, and ornamental Design for a Packaged Seed Display Stand, of which the following is a specification, reference being had to the accompanying drawing as forming a part thereof.

In the drawing:

Figure 1 is a front elevational view of a packaged seed display stand showing my new design; and,

Figure 2 is a side elevational view thereof.

Figure 3 is a vertical sectional view of the display stand shown in Figure 1 with the top panel member omitted.

I claim:

The ornamental design for a packaged seed display stand, as shown.

EARLE E. HUMPHRIES.
